CLAIM

The ornamental design for a display device for seatback mounting, as shown and described.

DESCRIPTION

FIG. 1 is a front perspective view of an embodiment of the display device for seatback mounting embodying the new design, shown mounted in a seatback in which the seatback forms no part of the claim;

FIG. 2 is a front perspective view of the embodiment of the display device for seatback mounting, shown separate from the seatback;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines in FIG. 1 showing the seatback depict environmental subject matter only and form no part of the claim; while all other broken lines in the drawings, including

(Continued)

the dotted lines seen in FIG. 4, depict portions of mounting structure that form no part of the claimed design.
